UNITED STATES PATENT OFFICE.

GEORGE ROBERT SISTERSON, OF LONDON, ENGLAND, ASSIGNOR TO SUPERHEATERS, LIMITED, OF LONDON, ENGLAND.

STEAM SEPARATOR AND HEATER.

No. 918,479.

Specification of Letters Patent.

Patented April 13, 1909.

Application filed December 18, 1907. Serial No. 407,045.

To all whom it may concern:

Be it known that I, GEORGE ROBERT SISTERSON, a subject of the King of Great Britain and Ireland, and residing at 12 Great James street, Bedford Row, London, W. C., England, have invented a certain new and useful Steam Separator and Heater, of which the following is a specification.

This invention relates to the treatment of steam for steam engines, and particularly of the steam for locomotives.

The object of the invention is to separate the water carried over with the steam from the boiler, so that only dry steam is allowed to go to the cylinders of the engine, and, further to vaporize the separated water so that economy is effected.

The invention consists in interposing a separator in the steam main, so as to separate the water carried over with the steam from the boiler, and in combining with the separator a heater, adapted to receive the separated water and to vaporize the same, so that the steam so generated can be fed to the steam which flows to the cylinders, thereby not only insuring dry steam but effecting economy.

The accompanying drawings illustrate several modes of carrying out the invention.

Figures 1 and 2 are sectional elevations of two forms of combined separator and heater applicable to the smoke box of a locomotive boiler. Fig. 3 a side view of the form shown in Fig. 2. Fig. 4 a sectional elevation of a further form applicable to the smoke box of a locomotive. Figs. 5 and 5^a are sectional views of a still further form. Figs. 6 and 7 are diagrammatic sectional elevations illustrating two applications to marine boilers of the Scotch type, that is to say, marine boilers which are fitted with return fire tubes.

In carrying out the invention according to one mode as illustrated in Fig. 1, the steam main, *a*, is led out through the smoke box end of the boiler, as usual. The main is then branched into two, so as to supply each cylinder. Each branch, *b*, leads to a suitable separator for instance, in the simple form shown in Fig. 1, this comprises a wall, *e*, provided with a number of perforations, *c*, through which the steam can pass to a branch, *d*, and thence by the usual steam pipe, *f*, to the cylinder. In striking the wall, *e*, and in endeavoring to pass the perforations,

c, the water carried over with the steam is separated and is thrown down into one side, *g*, of the header, *h*, of a heater of any suitable form. The heater in the form shown comprises a header, *h*, divided into two compartments, *g*, *i*, which are connected by a number of U-tubes, *k*, the U-tubes being passed into some of the fire tubes, *l*, of the boiler. Thus the water or wet steam which is thrown down into the compartment *g*, of the header, and which passes through the U-tubes, *k*, is heated, the water being vaporized and the steam to a certain degree superheated. This steam passing from the compartment, *i*, of the header mixes with the steam which flows through the perforations, *c*, into the branch, *d*, and thence, by the steam pipe, *f*, to the cylinder. Obviously, when there is but little water thrown down into the heater, some of the steam may pass freely through the heater, being thereby superheated or dried, and supplementing the separated steam which is led direct to the branch, *d*, thereby further raising the temperature of said steam or insuring the dryness thereof. In order to enable the fire tubes, *l*,—into which the U-tubes, *k*, are inserted—to be cleaned, openings, *m*, are provided in the header, *h*, through which a cleaning brush can be inserted.

In carrying out the invention according to another mode, as illustrated in Figs. 2 and 3, a similar form of separator is used, but the heater is in the form of tubes, *n*, which are led in any suitable manner either directly across or around the smoke box. For example, the tubes, *n*, may be extended straight across the ends of a row of fire tubes, being bent with an elliptical or circular bend, *o*, and a further loop, *p*, as shown in Fig. 2, care being taken to arrange the tubes so that a cleaning brush may be inserted in all the fire tubes. Obviously the tubes, *n*, may be bent or curved in any suitable manner, so as to give the desired heating surface.

In carrying out the invention according to a further mode, as illustrated in Fig. 4, the tubes, *n*, of the heater, instead of passing the steam directly by a single coil from the branch, *b*, to the branch, *d*, may lead it into one or more intermediate chambers or headers, *s*, thus extending the path of the steam through the tubes, *n*, and increasing the heating surface of the heater. It will be understood that any other suitable form of

heater and separator may be employed—for instance, a heater comprising a divided header and connected by a number of concentrically arranged tubes:

5 In the example shown in Fig. 4 a known arrangement of a number of tubes, *q*, are shown, in substitution for the usual single steam pipe which leads the steam to the cylinder, these tubes, *q*, adding to the available 10 heating surface within the smoke box and being connected at their ends to suitable headers—for instance, as indicated at *r*.

In the further form of apparatus shown in Fig. 5, the steam passes from the branch, *a*, 15 through the chamber 2, to the pipes 3, which are provided with enlarged portions, 4, at their upper ends into which project pipes, 5, communicating with the space, 6, from which the steam pipe to the cylinder leads. The 20 lower ends of the pipes, 5, act as separators, the water passing down into the lower ends of the pipes, 3, where it is vaporized. In this form, holes, *c*, are provided through which part of the steam passes directly to the space, 25 6, any separated water passing down into the tubes, 3.

Figs. 6 and 7 diagrammatically illustrate the application of the invention to marine boilers of the Scotch type, Fig. 6 showing a 30 case where a heater comprising tubes, *n*, arranged in the smoke stack or up-take, *t*, is used, whereas Fig. 7 shows a heater having tubes, *k*, entering some of the fire tubes, *l*, of the boiler. In marine boilers it may be desirable to arrange the separator outside of the up-take, *t*, for instance, as indicated in Figs. 6 and 7, the two chambers or branches, *b*, and *d*, of the separator being each provided with a stop valve, *u*, in order that the heater 35 may be cut out, if desired, for any particular purpose. In some cases it may be desirable to branch each of the portions, *v* and *w*, and to provide stop valves for controlling each branch, the heater being divided into two 40 portions, for instance in a somewhat similar manner to that described with reference to locomotive boilers. This arrangement would enable one part of the heater to be cut out, when desired, without interfering with the 45 working of the other part. It is obvious that more than one header may be used for each heater particularly in the forms shown in Figs. 1, 6 and 7, and it may be fitted with any 50 desired number of tubes; or a comparatively 55 large header, divided into a series of chambers, may be adopted. Instead of employing two combined separators and heaters, independently mounted upon the branch or steam pipes as hereinbefore described with 60 reference to Figs. 1, 2, 3 and 4 one separator may be fitted on the steam main before it branches into two, this single separator sup- 65 pling either a large header or two or more

small headers which can lead the steam generated from the separated water or the super- 65 heated steam into one or both of the branch pipes. It is obvious that the return ends of pipes, *n*, (Figs. 2 and 3) can be connected to any convenient point of the pipe, *f*, separation of the water being effected by simply 70 branching the T-piece.

The invention is applicable to the treatment 75 of steam from other boilers than locomotive or marine boilers, the heater and separator being suitably modified to suit the type 80 of boilers to which the invention is to be applied.

Having thus described my invention what I claim as new and desire to secure by Letters Patent is:—

1. In combination a steam main, a separator interposed therein comprising an inlet and an outlet compartment and means for baffling the steam passing from one compartment to the other, means connected with the 85 inlet compartment for receiving the water and wet steam deposited therein, means for heating said receiving means and a connection from the latter to the outlet compartment of the separator substantially as and 90 for the purposes hereinbefore set forth.

2. In combination a steam main, a separator interposed therein comprising an inlet and an outlet compartment, a perforated 95 wall dividing said compartments, a series of tubes connecting the bottom of one compartment with the bottom of the other and means for heating said tubes substantially as and for the purposes hereinbefore set forth.

3. In a locomotive fire-box, a steam main, 100 a separator therein, comprising inlet and outlet compartments, means for baffling the steam passing from the former to the latter, and tubes disposed in front of the usual fire tubes of the boiler, said tubes being connected to the aforesaid compartments of the separator to receive the deposited water and wet steam and to return it as dry steam to the main.

4. In a locomotive fire-box, a steam main, 110 a separator thereon comprising inlet and outlet compartments, perforated walls between the compartments for baffling the steam passing therethrough, and tubes disposed in front of the usual boiler fire tubes, said tubes 115 being connected to the aforesaid compartments of the separator to receive the deposited water and wet steam and to return it as dry steam to the main.

In testimony whereof I have signed my 120 name to this specification in the presence of two subscribing witnesses.

GEORGE ROBERT SISTERSON.
